LOADER MECHANISM

Ernest J. Gildner, Cheboygan, Mich.

Application July 13, 1955, Serial No. 521,803

8 Claims. (Cl. 214—140)

This invention relates to hydraulic, power loading devices for loading gravel and loose, fragmentary material and products of all kinds, and specifically to a device which is readily attachable to a standard tractor and operable by power supplied by said tractor.

One of the prime objects of the invention is to provide a loading device having loader mounting brackets which are mounted directly on the heavy duty tractor cross members or truck frame in a manner to carry all load and stress created by the loading operation, thus relieving the tractor frame of undue stress and strain.

A further object is to design a loading attachment for a bulldozer or tractor in which the tractor operates a minimum distance backward or forward to perform the loading operation the loader being operable through a 185° angle and thus eliminating the necessity of turning movement and the side thrusts and strains incident thereto.

A further object still is to provide a loader attachment of rugged and substantial construction which can work from both ends and on which all loads and stresses, due to loading and unloading, are absorbed by the tractor frame permitting the tracks to function in exactly the same manner as a tractor with the attachment removed.

Still a further object is to provide a loader attachment, the bucket of which swings overhead from the front to the rear, permitting the load to be dumped without turning the tractor, and with minimum of travel thereof, to thereby minimize wear and side thrust in general.

Still a further object is to provide a loader attachment on which the side bars can be set sufficiently low to provide a straight-line push on the bucket or blade when loading or bulldozing, thus eliminating the tendency to lift the tractor, making for balanced loading, and eliminating racking of the bucket structure.

With the above and other objects in view, the present invention consists in combination and arrangement of parts, hereinafter more fully described, illustrated in the accompanying drawings, and more particularly pointed out in the appended claims, it being understood that changes may be made in the form, size, proportion and minor details of construction, without departing from the spirit, or sacrificing any of the advantages of the invention.

In the drawings:

Fig. 1 is a side elevational view of a conventional tractor with my improved loader attachment in place thereon, the solid lines showing a tractor bucket loading, the broken lines indicating the tractor travel and the path of swinging movement of the bucket as it is swung from loading position into a position for dumping into a truck.

Fig. 2 is a top plan view of the tractor and attachment.

Fig. 3 is a view similar to Fig. 1 with the truck omitted, the broken lines showing various possible positions of the bucket.

Referring now more particularly to the drawings in which I have shown the preferred embodiment of my invention, the numeral 5 indicates a conventional tractor of the caterpillar type, including continuous treads 6,

2

and a frame 7 with fabricated loader mounting brackets 8 rigidly secured thereto on opposite sides of the tractor as shown.

A bearing 9 is provided in each loader bracket 8 and to which one end of each attachment arm 10 is pivotally connected as usual. A plate 11 is welded to each free end of the side attachment arms 10 and is bolted to the end plates of heavy tubular spacer members 12 to properly space said arms from each other and prevent interference with the tractor structure as the bucket is swung.

A bucket B is disposed directly ahead of the sleeve 12 and spaced apart pairs of clips 13 are welded thereto. Bracket arms 14 are mounted on the spacer sleeve 12 with their outer ends pivotally connected to the clips 13 by bolts 15. Other pairs of clips 16 are also welded to the bucket B in spaced relation.

Angularly disposed spaced apart mounting brackets 17 are provided on the sleeve 12 and hydraulic tilt cylinders 18 are pivotally connected to said brackets by means of pins 19, the piston rods 20 being connected to the bracket clips 16 by means of pins in the usual manner.

Hydraulic lines 21 and 22 connected to the opposite ends of the tilt cylinder 18, and to a suitable source of power supply (not shown) provided on the tractor, and it will be obvious that the tilt of the bucket can be readily controlled by said hydraulic tilt cylinders.

The bucket raising means comprises the main lift cylinders 24 connected at the one end to ear clips 25 provided on the sleeve 12. A piston rod 26 is slidable in each cylinder as usual, said rod projecting from the opposite end of each cylinder and being pivotally connected to the A-frame loader mounting frame 8 by means of pins 27. The hydraulic lines 28 lead from each cylinder 24 to the source of power supply on the tractor. This arrangement serves to swing the bucket up and over the tractor so that the load can be dumped into a truck T, all as indicated in broken lines in Fig. 1, after which the bucket is again returned to loading position.

Briefly, the operation of the loader is as follows: With the tractor and bucket in position shown in broken lines at E, the operator drives the tractor in the direction, indicated by a solid arrow, to fill said bucket. When the bucket B is loaded, the tractor is reversed to move it back to the original position. The main lift cylinders 24 then raise the bucket and swing it over the tractor, and simultaneously the bucket lift cylinders 18 are operated to control and hold the bucket in position to prevent spillage of the "load" until it is swung over the truck, once the bucket is near to a position over the truck the bucket is allowed to pivot about the hinge pins 13 to discharge its load. With this arrangement there is no swinging movement nor travel of the tractor, consequently, side thrusts and strains are eliminated. There is a minimum of tractor travel, because the tractor moves but a limited distance back and forth, the bucket being swung over the truck and thus saving considerable time and increasing the efficiency and life of the tractor and associated loader parts.

From the foregoing description it will be obvious that I have perfected a very simple, practical, and substantial power loading mechanism which can be readily and quickly attached to and/or detached from a conventional tractor.

65 What I claim is:

1. In a crawler type vehicle overshot loader, a mobile frame, a loader-mounting bracket mounted on each side of said frame, loader arms pivotally connected to said mounting brackets, a spacer member connecting the outer end of said arms and a bucket hingedly connected to the outer end of said loader arms lift cylinders pivot-

ally connected to said spacer member, a piston rod assembly slidably mounted in each cylinder and pivotally connected to the upper ends of each mounting bracket, and tilt cylinders mounted on said spacer and pivotally connected to said bucket.

2. The combination as in claim 1 in which the mobile frame includes spaced apart shafts and wheels, continuous treads trained thereover with the ends of the loader arms hingedly connected to said mounting brackets at a point in substantial horizontal alignment with said shafts, said bucket being swingable over said vehicle.

3. The combination as defined in claim 1, in which the tilt cylinders are connected to said bucket at a point above the horizontal center line thereof.

4. In a vehicle loader attachment for a mobile frame; a loader mounting bracket for mounting on each side of said frame; a loader assembly including a pair of spaced apart arms and a bucket hingedly carried by said arms near their front ends; the rear ends of said arms being pivotally connected to said mounting brackets; at least one extensible, fluid pressure, lift cylinder disposed in a vertical plane out of the vertical planes of said arms pivotally connected to one of said mounting brackets at a spaced distance above the connection of said arms, and to said assembly near the front ends of said arms for swinging said arms through an arc of substantially 180°, the cylinder having a piston rod assembly in extended position when the arms are swung down so that the bucket is near ground level; and at least one extensible fluid pressure tilt cylinder supported by said arms and connected to the bucket at a point offset from the hinged connection thereof for tilting said bucket.

5. In a vehicle loader attachment for a mobile frame; a loader mounting bracket carried by said frame near each side of said frame; a loader assembly including arms and a carrier hingedly supported by said arms near their front ends, said arms being pivotally connected to said mounting brackets at their rear ends; at least one power operated, extensible, lift member disposed in a vertical plane out of the vertical plane of said arms pivotally connected to one of said brackets at a point a spaced distance above the connection of said arms and to said assembly near the front ends of said arms for swinging said arms through a substantial arc over the top of the vehicle, said lift member having an extensible member in extended position when the arms are swung down so that the carrier is near ground level; and remotely controlled means operable to tilt said carrier while the arms are traveling in said arc.

6. In a vehicle loader; a mobile frame; a loader mounting bracket fixed on each side of said frame; a loader assembly including a pair of spaced apart arms and a carrier hingedly carried by said arms near their front ends, the rear ends of said arms being pivotally connected to said mounting brackets; extensible fluid pres-

sure lift cylinders disposed in vertical planes out of the vertical planes of said arms pivotally connected to said mounting brackets at a spaced distance above the connection of said arms and to said assembly near the front ends of said arms for swinging said arms through an arc of substantially 180°, the cylinder having a piston rod assembly in extended position when the arms are swung down so that the bucket is near ground level and at least one extensible fluid pressure tilt cylinder connected between said arms and bucket for tilting said bucket.

7. In a vehicle loader, a mobile frame; axle shafts carried by said mobile frame for supporting vehicles thereon, a loader mounting bracket carried by said frame near each side of said frame; a loader assembly including arms and a carrier hingedly supported by said arms near their front ends, said arms being pivotally connected to said mounting brackets at their rear ends at points substantially in horizontal alignment with said axle shafts; at least one power operated, extensible, lift member disposed in a vertical plane out of the vertical plane of said arms pivotally connected to one of said brackets at a point a spaced distance above the connection of said arms and to said assembly near the front ends of said arms for swinging said arms through a substantial arc over the top of the vehicle from either end, said lift member having an extensible member in extended position when the arms are swung down so that the carrier is near ground level; and remotely controlled means connected to said carrier for tilting said carrier while said arms are traveling in said arc.

8. In a vehicle loader; a mobile frame, a loader mounting bracket carried by said frame near each side of said frame; a loader assembly comprising arms and a bucket hingedly supported by said arms near their front ends, said arms being pivotally connected to said mounting brackets at their rear ends; at least one power operated extensible lift member disposed in a vertical plane out of the vertical plane of said arms pivotally connected to one of said brackets at a point a spaced vertical distance from the connection of said arms and to said arms for swinging said arms through a substantial arc over the top of the vehicle, said lift member having an extensible member in extended position when the arms are swung down so that the carrier is near ground level; and remotely controlled means connected to said carrier for tilting said carrier while it is traveling in said arc.
